UNITED STATES PATENT OFFICE.

MILTON Z. SIMS, OF AURORA, ILLINOIS.

BRAKE-WHEEL.

SPECIFICATION forming part of Letters Patent No. 694,686, dated March 4, 1902.

Application filed December 26, 1901. Serial No. 87,255. (No model.)

To all whom it may concern:

Be it known that I, MILTON Z. SIMS, a citizen of the United States, residing at Aurora, in the county of Kane and State of Illinois, have invented certain new and useful Improvements in Brake-Wheels, of which the following is a specification.

This invention relates particularly to that class of brake-wheels which are termed "tip-over" wheels, and particularly to the construction and arrangement of the parts by which the brake-wheel may be held in operative position so as to be rotated in a horizontal plane and thrown or "folded" over into a vertical plane and out of position, as will more fully hereinafter appear.

The principal object of the invention is to provide a simple, economical, and efficient foldable brake wheel and shaft of such construction and arrangement that the brake-wheel may be held in operative position so as to rotate in a horizontal plane or folded over into a vertical plane and out of operative position.

25 Further objects of the invention will appear from an examination of the drawings and the following description and claims.

The invention consists principally in a brake-shaft and brake-wheel foldably secured together, in combination with spring mechanism for yieldingly holding them in their different positions.

30 The invention consists, further, in a tip-over brake-wheel in which there is combined a brake-shaft, a brake-wheel pivotally secured thereto, and spring mechanism secured to the brake-shaft for yieldingly holding the brake-wheel in its different positions.

The invention consists, further, in a tip-over 35 brake-wheel in which there is combined a brake-shaft having a bifurcated end, a brake-wheel, a stud upon which such brake-wheel is mounted pivotally secured in the bifurcated end of the brake-shaft, and spring mechanism for yieldingly holding the brake-wheel in its different positions.

The invention consists, further, in a tip-over 40 brake-wheel in which there is combined a brake-shaft provided with a bifurcated end, a brake-wheel, a stud upon which such brake-wheel is mounted provided with a flattened angular end portion pivotally secured in the bifurcated end of the brake-shaft, and a flat steel

spring secured to the brake-shaft and provided with a free end, forming a recess to engage the angular portion of the brake-wheel stud and yieldingly hold such wheel in its different positions.

The invention consists, further and finally, in the features, combinations, and details of construction hereinafter described and claimed.

In the accompanying drawings, Figure 1 is a plan sectional view of two passenger-coaches, one provided with an ordinary platform and the other with a vestibule-platform, coupled together, showing my improvements attached thereto in operative and inoperative positions; Fig. 2, an end view of a portion of a passenger-coach provided with a brake-wheel constructed in accordance with these improvements; Fig. 3, an enlarged elevation, partly in section, of a brake shaft and wheel constructed in accordance with these improvements, the full lines showing the parts in operative position and the dotted lines showing the brake-wheel in its inoperative position; Fig. 4, a perspective view of the brake-wheel stud, and Fig. 5 a perspective view of the upper end of the brake-wheel shaft.

In the art to which this invention relates it is well known that ordinary passenger-coaches are provided with brake-wheels attached to vertical brake-shafts in such a manner that such wheels must rotate in a horizontal plane. The principal objection to this arrangement is that when coupled with a vestibule-coach the brake-wheel is liable to interfere with the vestibule portion thereof. It is also well known that when this class of cars is coupled with vestibule-coaches it is quite common to remove the brake-wheel from its connection with the brake-shaft and hang it over the same and out of the way, which is not only objectionable from the fact of its having to be removed, but, further, in that it cannot always be readily and quickly put into position for operative use should occasion require. It is further well known that when the ordinary brake-wheel is in position on an ordinary coach it interferes with the loading and unloading of passengers, those getting on the car quite often striking their garments and persons against the brake-wheel, thereby causing them sometimes considerable damage and annoyance.

The principal object of this invention, therefore, is to provide a brake-wheel of such construction as to be foldable into operative and inoperative position quickly and readily whenever occasion requires or necessity demands.

In illustrating and describing these improvements I have only illustrated and described so much as is old, taken in connection with what I consider to be new, as will properly disclose the invention and enable those skilled in the art to practice the same, leaving out of consideration other and well-known elements which if illustrated and described herein would only tend to confusion, prolixity, and ambiguity.

In constructing a brake-wheel in accordance with these improvements and using it in connection with a passenger-coach *a*, I provide a vertical brake-shaft *b*, which is connected at its lower end by means of a chain *c* with the ordinary braking mechanism, all of which is well known in this art. It will be seen that it is necessary to rotate this brake-wheel in one direction so as to operate the ordinary braking mechanisms (not shown) and permit it to be rotated in the other direction for the release of the same. In order to provide a wheel therefore for operating this shaft and arrange it in such manner as to permit of its being moved into and out of operative position when desired, I provide the brake-shaft with an upper bifurcated end slotted, as at *d*. I next take a brake-wheel *e* and mount it upon a square portion of a wheel-stud *f*, so that it cannot be rotated independent of such stud, the wheel and stud being held in engagement with each other by means of a locking-nut *g*. The lower part of this wheel-stud is provided with a flattened angular portion *h*, which is perforated, as at *i*, so that it may be pivotally secured in the slot formed in the bifurcated end of the brake-shaft, as shown in Fig. 3.

In Fig. 3 it will be seen that the brake-wheel is illustrated in full lines and may be swung into operative position, but, as shown in dotted lines, that it may be swung out of operative position or folded out of the way. It becomes necessary, therefore, to provide some means by which these parts—the brake-shaft and brake-wheel—may be held yieldingly in engagement with each other, so as to permit them to perform the desired operations and at the same time permit the brake-wheel to be readily and easily moved. In order to accomplish this result, a tension-spring *k* is provided and secured, as shown in Fig. 3, to the brake-shaft. The upper free end of this spring is so formed as to provide a pocket or recess *l*, the counterpart of the angular ends of the brake-wheel stud. The construction is such that when the brake-wheel has been moved into the position shown in Fig. 3 in full lines the wheel will span the angle *m* of the stud and yieldingly hold it, with its brake-wheel, in operative position. When the parts are moved into the position shown in dotted

outline in the same figure, the free end of the spring engages and yieldingly holds the angle *n* of the brake-stud, thereby holding the parts in their inoperative position and out of the way, all of which will be appreciated by those skilled in the art.

There are many advantages incident to the use of a foldable brake-wheel constructed in accordance with these improvements, as will be seen from an examination of Fig. 1, which shows it attached to an ordinary coach, which coach is coupled with a passenger-coach having a vestibule-platform *p*. In dotted outline in this figure the brake-wheel is shown in operative position, so that it is not only liable to interfere with the vestibule, but also with the loading and unloading of passengers. The full lines in Fig. 1 show the brake-wheel in its inoperative position and out of the way, while at the same time permitting it to be readily thrown into operative position as occasion requires.

I claim—

1. In a tip-over brake-wheel, the combination of a brake-shaft and brake-wheel with spring mechanism for yieldingly holding them in their different positions, substantially as described.

2. In a tip-over brake-wheel, the combination of a brake-shaft, a brake-wheel pivotally secured thereto and a spring secured to the brake-shaft for yieldingly holding the brake-wheel in its different positions, substantially as described.

3. In a tip-over brake-wheel, the combination of a brake-shaft having a bifurcated end, a brake-wheel, a stud upon which such brake-wheel is mounted pivotally secured in the bifurcated end of the brake-shaft, and spring mechanism for yieldingly holding the brake-wheel in its different positions, substantially as described.

4. In a tip-over brake-wheel, the combination of a brake-shaft provided with a bifurcated end, a brake-wheel, a stud upon which such brake-wheel is mounted and provided with a flattened angular end portion pivotally secured in the bifurcated end of the brake-shaft, and a flat steel spring secured to the brake-shaft and provided with a free end providing a recess to engage the angular portion of the brake-wheel stud and yieldingly hold such wheel in its different positions, substantially as described.

5. In a brake-wheel, the combination of a brake-shaft having a bifurcated end, a brake-wheel, a stud upon which such brake-wheel is mounted pivotally secured in the bifurcated end and provided with a limiting-shoulder to bear against the brake-shaft in one position, and spring mechanism for yieldingly holding the brake-wheel in its different positions, substantially as described.

MILTON Z. SIMS.
